UNITED STATES PATENT OFFICE

HARLEY J. EARL, OF DETROIT, MICHIGAN, ASSIGNOR TO GENERAL MOTORS CORPORATION, OF DETROIT, MICHIGAN, A CORPORATION OF DELAWARE

DESIGN FOR A RUNNING BOARD

Application filed August 18, 1928. Serial No. 27,883. Term of patent 14 years.

To all whom it may concern:

Be it known that I, HARLEY J. EARL, citizen of the United States, and resident of Detroit, county of Wayne, State of Michigan, have invented a new, original, and ornamental Design for a Running Board, of which the following is a specification, reference being made to the accompanying drawing, forming a part thereof.

In the drawing:

Figure 1 is a side view of an automotive vehicle showing the running board of the invention.

Figure 2 is a perspective view of the running board.

Figure 3 is a section through Figure 2.

I claim:

The ornamental design for a running board as shown.

HARLEY J. EARL.
